MASK STRUCTURE

James Edward Duggan, Birmingham, Mich.

Application April 20, 1944, Serial No. 531,956

6 Claims. (Cl. 204—297)

1

This invention relates generally to devices that are used during painting or plating operations to protect certain portions of articles from paint or plating material applied to adjacent portions thereof, and refers more particularly to masking elements for preventing paint or plating material from contacting or passing onto opposite sides of an article, such for example, the inside and outside of a tubular or annular article while opposite ends of such article are painted or plated.

One of the essential objects of the invention is to provide a two-part mask structure wherein both parts may be employed at one time for masking simultaneously both the inside and outside of a tubular or annular article, or either of said parts may be employed alone for masking one of said sides, depending upon which one is to be masked.

Another object is to provide a mask structure wherein the two parts thereof are shaped to provide a vacuum between such parts and the sides of the tubular or annular article intermediate opposite edges or ends thereof when the parts are applied to said sides, and are adapted to exert the greatest pressure against said sides adjacent opposite edges or ends thereof for sealing purposes.

Another object is to provide a mask structure that is shaped in such a way relative to the faces of the article to be protected that it not only will have a tight sealing engagement with the article but also will have a vacuum lock with the article and thus will be maintained in proper masking position relative thereto.

Another object is to provide a mask structure that is capable of protecting the portions of the article to be masked without interfering with the painting or plating operations.

Another object is to provide a mask structure wherein one part thereof may be utilized with a hanger or supporting wire as a carrier for the other part as well as the article being painted or plated while such painting or plating operations are being performed.

Another object is to provide a mask structure that may be easily and quickly applied to and removed from the article to be masked without marring or impairing any part thereof.

Another object is to provide a mask structure that may be used repeatedly without being scrapped.

Another object is to provide a mask structure that is simple in construction, economical to manufacture, and efficient in operation.

5

Other objects, advantages and novel details of construction of this invention will be made more apparent as this description proceeds, especially when considered in connection with the accompanying drawing, wherein:

Figure 1 is a plan view of a masking structure applied to an annular article, and showing parts broken away and in section;

Figure 2 is an elevational view of the structure illustrated in Figure 1;

Figure 3 is a vertical sectional view through the structure illustrated in Figure 2;

Figure 4 is a detail elevational view of the inner part of the masking structure;

15 Figure 5 is a plan view of the outer part of the masking structure;

Figure 6 is an edge elevational view of the annular article.

Referring now to the drawing, A is a tubular or annular article constituting a race or spacer for a connecting rod (not shown) on the crank shaft of an airplane engine, and B is a masking structure embodying my invention having inner and outer sections or parts 10 and 11, respectively, of rubber or rubber composition for protecting the inside 12 and outside 13 of said article from paint or plating material applied to opposite ends or edges 14 and 15, respectively, thereof.

20 30 As shown the inner section 10 of the masking structure is preferably in the form of an elongated plug having a body 20 provided exteriorly thereof with an annular groove or recess 21 and provided at one end with a knob or finger piece 22. Preferably the body 20 is slightly oversize relative to the inside of the annular article so that it has to be compressed slightly to be applied thereto.

40 The outer section 11 of the masking structure is preferably in the form of an annulus and has a radially extending boss 40. Preferably the outer section 11 is slightly undersize relative to the outside of said annular article so that it has to be stretched slightly to be applied thereto. An annular groove or recess 41 is provided in the inner face of the annulus, while the passage 42 extends radially of the annulus and throughout the length of the boss 40 for the reception of a supporting wire or hanger 43.

45 50 55 In use when opposite ends 14 and 15, respectively, of the article A are to be plated, the inner and outer sections 10 and 11 of the masking structure are engaged with the inside and outside, respectively, of the article as illustrated in Figure 3, to effect the desired masking operation. When

the sections 10 and 11 are in this position the annular portions 50 and 51, respectively, of the section 11 are in pressure sealing engagement with the outside of the article adjacent opposite ends thereof, and the peripheral portions 52 and 53, respectively, of the section 10 are in pressure sealing engagement with the inside of the article, hence a vacuum is created at 60 between the outer section 11 and the outside of the article, and a vacuum is created at 61 between the inner section 10 and the inside of the article. As a result, the sections 10 and 11 of the masking structure tightly engage the inside and outside of the article from one end to the other thereof and effectively prevent plating material applied to said ends of the article from contacting or reaching the sides thereof.

The supporting rod or wire 43 closes the passage 42 and is provided at its inner end with a spring pressed electric contact 70 for engagement with the outside of the article. At its outer end the wire 43 has a hooked portion 71 for supporting engagement with a conventional bus bar (not shown) of suitable plating apparatus. Usually this wire 43 is suspended from the bus bar so that the article A will be received within the usual tank (not shown) containing the plating material.

The spring 72 for the contact 70 may be connected at one end to the wire 43 and may carry the electric contact 70 at its other end, or any other suitable connection may be utilized for carrying the contact 70 from the wire 43 for proper electrical engagement with the outside of the article A.

Due to the connection between the supporting wire 43 and the outer section 11 of the masking structure and the tight engagement of both sections 10 and 11 of the masking structure with the article A, it is apparent that the wire 43 is utilized as a common carrier for the article and the entire masking structure therefor when such elements are suspended by the wire from the bus bar of the plating apparatus.

Sometimes it may be desired to plate the inside of the article A as well as opposite ends thereof without plating the outside thereof, in which event it is necessary to mask only the outside of the article. Then the inner section 10 would not be employed at all. Only the outer section 11 would be engaged with the outside of the article so that the latter and said outer section may be suspended by the wire 43 from the bus bar to permit plating material within the tank of the plating apparatus to contact the inside and opposite ends of the article. The outer section 11 would effectively prevent such plating material from contacting the outside of the article.

Likewise the outside of the article as well as opposite ends thereof may be plated while the inside of such article is masked by the inner section 10.

If painting instead of plating operations are employed, then the wire 43 may in each instance be used merely as a support or hanger for the masking structure and the article carried thereby without being utilized as an electrical conductor from a bus bar. In fact, the boss 40 alone or the knob 22 alone may then be used by the operator as a means by which the sections of the masking structure and the article carried thereby may be supported during such painting operations.

Thus, from the foregoing, it will be apparent that I have provided an efficient masking struc-

ture that has quite universal use during either painting or plating operations to protect one or more parts of the article to be painted or plated.

By referring to Fig. 3 it will be noted that the masking elements 10 and 11 have cooperating beveled portions 80 and 81 for directing paint or plating material toward the end portions 14 and 15 respectively of the annular member A. The beveled portions 80 of the masking element 10 are upon opposite sides of and incline toward the groove 21, and are alternately engageable with opposite edges of the annular member A to facilitate insertion of the body 20 endwise into the annular member. The beveled portions 81 of the masking element 11 are upon opposite sides of and incline toward the groove 41, and are alternately engageable with opposite edges of the annular member A to facilitate movement of the masking element 11 onto the exterior of the annular member A. It will also be noted that the knob 22 of the masking element 10 has an axially extending passage 82 for the reception of a supporting wire or hanger (not shown). The body portion 20 of the masking element 10 is provided from its lower end to the passage 82 with an axially extending socket 83 that is adapted to receive the lower end portion (not shown) of a supporting wire or hanger for the masking element 10, and to permit sufficient contraction 30 of the body portion 20 for proper insertion of the peripheral portions 52 and 53 respectively of the body into the annular member for sealing engagement with the inner surface thereof.

What I claim as my invention is:

35. 1. Means for protecting the outer surface of an annular member from paint or plating material applied to other portions of said member, comprising a masking element having an annular body of resilient material and adapted to be sleeved upon said annular member to substantially cover the outer surface thereof, said annular body being provided in its inner face with an annular concave groove adapted to cooperate with the outer surface of the annular member to create a vacuum and having beveled portions upon opposite sides of and inclining toward said groove, said beveled portions being alternately engageable with opposite edges of the annular member to facilitate sleeving of the body upon 45 the annular member, said body being slightly undersize relative to the outside of and adapted to be stretched upon said annular member so that the annular portions of the body between said beveled portions and groove will have pressure 50 sealing engagement with the outer surface of said annular member.

2. Means for protecting the outer surface of an annular member from paint or plating material applied to other portions of said member, 60 comprising a masking element having an annular body of resilient material and adapted to be sleeved upon said annular member to substantially cover the outer surface thereof, said annular body being provided in its inner face with an annular concave groove adapted to cooperate with the outer surface of the annular member to create a vacuum, said body being slightly undersize relative to the outside of and adapted to be stretched upon said annular member so that 65 the portions of the body upon opposite sides of said groove will have pressure sealing engagement with the outer surface of said annular member.

3. Means for protecting the outer surface of 70 an annular member from paint or plating ma-

terial applied to other portions of said member, comprising a masking element having an annular body of resilient material and adapted to be sleeved upon said annular member to substantially cover the outer surface thereof, said annular body being provided in its inner face with an annular concave groove adapted to cooperate with the outer surface of the annular member to create a vacuum and having beveled portions upon opposite sides of and inclining toward said groove, said beveled portions being alternately engageable with opposite edges of the annular member to facilitate sleeving of the body upon the annular member, said body being slightly undersize relative to the outside of and adapted to be stretched upon said annular member so that the annular portions of the body between said beveled portions and groove will have pressure sealing engagement with the outer surface of said annular member, said body being provided at the outer side thereof with a radially projecting portion, and means for conducting an electric current radially through the masking element to the annular member, including a support for both the masking element and annular member extending lengthwise of said radially projecting portion and having a hook-shaped portion engageable with a bus bar.

4. Means for protecting the outer surface of an annular member from paint or plating material applied to other portions of said member, comprising a masking element having an annular body of resilient material and adapted to be sleeved upon said annular member to substantially cover the outer surface thereof, said annular body being provided in its inner face with an annular concave groove adapted to cooperate with the outer surface of the annular member to create a vacuum, said body being slightly undersize relative to the outside of and adapted to be stretched upon said annular member so that the portions of the body upon opposite sides of said groove will have pressure sealing engagement with the outer surface of said annular member, said body being provided at the outer side thereof with a radially projecting portion, and means for conducting an electric current radially through the masking element to the annular member, including a support for both the masking element and annular member extending lengthwise of said radially projecting portion and having a hook-shaped portion engageable with a bus bar.

5. Means for protecting the outer surface of an annular member from paint or plating material applied to other portions of said member, comprising a masking element having an annular body of resilient material and adapted to be sleeved upon said annular member to substantially cover the outer surface thereof, said annular body being provided in its inner face with an annular concave groove adapted to cooperate with the outer surface of the annular member to create a vacuum, said body being slightly undersize relative to the outside of and adapted to be stretched upon said annular member so that the portions of the body upon opposite sides of said groove will have pressure sealing engagement with the outer surface of said annular member, and a common support for the masking element and annular member including an electrical conductor extending radially through said masking element and provided within the concave groove aforesaid with means for establishing an electrical connection with said annular member.
6. Means for protecting the outer surface of an annular member from paint or plating material applied to other portions of said member, comprising a masking element having an annular body of resilient material and adapted to be sleeved upon said annular member to substantially cover the outer surface thereof, said annular body being provided in its inner face with an annular concave groove adapted to cooperate with the outer surface of the annular member to create a vacuum and having beveled portions upon opposite sides of and inclining toward said groove, said beveled portions being alternately engageable with opposite edges of the annular member to facilitate sleeving of the body upon the annular member, said body being slightly undersize relative to the outside of and adapted to be stretched upon said annular member so that the annular portions of the body between said beveled portions and groove will have pressure sealing engagement with the outer surface of said annular member, and a common support for the masking element and annular member including an electrical conductor extending radially through said masking element and provided within the concave groove aforesaid with means for establishing an electrical connection with said annular member.

JAMES EDWARD DUGGAN.
